UNITED STATES PATENT OFFICE.

EDWARD POSSON, OF PARK RIDGE, ILLINOIS.

TANK OUTLET VALVE AND OPERATING MECHANISM THEREFOR.

1,426,008.

Specification of Letters Patent. Patented Aug. 15, 1922.

Application filed August 27, 1920. Serial No. 406,299.

To all whom it may concern:

Be it known that I, EDWARD POSSON, a citizen of United States, residing at Park Ridge, in the county of Cook and State of Illinois, have invented a certain new and useful Improvement in Tank Outlet Valves and Operating Mechanism Therefor, of which the following is a full, clear, concise, and exact description, reference being had 10 to the accompanying drawings, forming a part of this specification.

This invention relates to improvements in tank outlet valve and operating mechanism therefor.

15 One object of the invention is to provide a simple and efficient outlet valve and operating mechanism therefor of economical manufacture and which is especially adapted for use on tank cars.

20 More specifically, the object of the invention is to provide an operating mechanism for tank car outlet valves wherein are employed an operating handle and cooperating parts so associated that the operating 25 handle will automatically position itself in inoperative position when the outlet valve proper is closed and a locking device will come into action to insure maintenance of the operating handle in said position.

30 Other objects of the invention will more clearly appear from the description herein-after following.

In the drawings forming a part of this specification, Figure 1 is a vertical part sectional, part elevational view of the central portion of a tank car showing my improvements in connection therewith. Figure 2 is an enlarged vertical sectional view of the upper end of the valve rod or shaft showing 40 the details of the operating handle lock and immediately associated parts. In this view the full line position of the handle corresponds to its operative position and the dotted line position corresponds to the inoperative 45 or locked position of the handle. Figure 3 is a top plan view of the parts shown in Figure 2. In Figure 3 the full line position of the handle corresponds to the operative position thereof, that is, when the valve 50 is open for discharge, and the dotted line position is that corresponding to the closed condition of the outlet valve. Figure 4 is a detail sectional view corresponding substantially to the line 4-4 of Figure 2. And Figure 5 is a detail sectional view in a vertical 55 plane extending parallel to the center sills

of the car illustrating the construction of the valve proper and discharge outlets.

I have shown my improvements as especially adapted for a railway tank car, for 60 the reason that the improvements possess special utility in this connection but it will be understood by those skilled in the art that the invention is susceptible to use in other fields without departing from the spirit of 65 the invention.

In said drawings, 10 denotes the tank of the usual tank car, the same having a dome 11 on the top thereof with a removable cap 12 of any well known or desired form. The 70 tank is of course filled through the dome 11, the upper portion of the tank having an opening 13 therein located centrally of the dome 11. The discharge or outlet valve proper is located at the bottom of the tank 75 as indicated at A.

Said outlet or discharge valve, as best indicated in Figure 5, comprises a casting 14 which forms the valve casing, said casting 14 having a laterally extended flange 15 secured to the lower main tank sheet of the tank, the valve casing being extended upwardly through an opening in said tank sheet as clearly shown in Figure 5. The valve casing has diametrically disposed 80 openings 16-16 in the sides thereof with which are adapted to register corresponding openings 17 in the valve plug 18. The exterior surface of the plug 18 and the interior surface of the valve casing are 85 machined to thereby provide a tight seal, said machined surfaces being tapered downwardly as indicated in Figure 5. The bottom end of the plug 18 is open as indicated at 90 19 so that the contents of the tank are adapted to discharge into the outlet pipe 20 which passes downwardly between the center sills of the car. The upper end of the valve 95 casing has applied thereto a cap plate 21 by means of bolts 22 or other suitable fastening devices, there being a spring 23 interposed between said cap 21 and the top of the valve plug 18. With this construction, it is obvious that the spring 23 normally exerts a pressure downwardly on the valve 100 plug to maintain the latter in proper relation with the valve casing.

The outlet pipe 20 is secured to the valve casing 14 by a plurality of bolts 24 which pass through perforated ears 25 on the 110 outlet pipe 20, the heads of the bolts 24 being hooked over slotted lugs 26 on the

bottom of the casting 14. Only one of such bolts is shown in Figure 5 but it will be understood that several of the same will be employed uniform in spacing around the 5 outlet pipe. A lead or other suitable sealing gasket 27 may be employed between the opposed faces of the outlet pipe and the casting 14. The bottom of the outlet pipe 20 is exteriorly threaded as indicated at 10 28 to adapt the same for connection with a pipe when the tank is discharged. It frequently occurs that connecting pipes for discharge are of different diameters and in order to adapt the tank car for connection 15 with such different sized pipes, I employ what may be termed a reducing union 29 having the upper flange 30 thereof of sufficiently enlarged diameter to fit over the threads 28. Said union 29 at its lower end 20 is exteriorly threaded as indicated at 31 so as to adapt it for the reception of a sealing cap or nut 32. A lead or other suitable material seal 33 may be employed between the union 29 and the bottom edge of the outlet pipe 20. In order that the reducing union 29 may be detachably held in operative position while at the same time made 25 easily displaceable without danger of loss, I employ the following arrangement. The 30 outlet pipe 20 is provided with a plurality of radially extended sets of spaced ears or lugs 34 within one set of which is pivotally attached a link 35. The lower end of the link has an elongated slot 36 through which 35 extends a pin or rivet 37 carried by a pair of radially extended ears or lugs on the union 29. To the other sets of ears or lugs 34 of the outlet pipe are pivotally attached bolts 38 adapted to engage within slotted 40 extensions 39 formed on the union 29. Each of said bolts 38 is adapted to receive a loop nut 40 by which the union 29 may be tightened on.

With the construction described, it is 45 obvious that a pipe corresponding in diameter to the diameter of the lower end of the outlet pipe 20 may be used when the union 29 is dropped down out of the way or a pipe of smaller diameter may be connected to the threaded portion 31 of the union 29 upon removal of the cap 32. The 50 arrangement is simple and there is no danger of the reducing union becoming lost or misplaced or any of the parts immediately 55 associated therewith.

The plug 18 has riveted or otherwise rigidly secured thereto an operating shaft or rod 41 which extends upwardly through a suitable bearing provided therefor in the 60 cap plate 21 and through an opening 42 in the upper sheet of the tank and within the dome 11. Secured to the top side of the upper tank sheet is a casting 43 having a flange 44 by which the same is riveted to 65 the tank sheet. Said casting 43 has an up-

wardly extended hollow boss 45 with an opening 46 therein arranged to act as a bearing for the upper end of the shaft or rod 41. Secured to the upper end of the rod 41, which may be reduced and squared as 70 indicated at 47 for the purpose, is a carrier casting 48. Said casting 48 or carrier, is slotted on its under side as indicated at 75 49 and within the slotted portion is pivotally connected an operating handle 50 by means of the rivet or pin 51. As will be clearly seen from an inspection of Figure 2, the handle 50 may assume either a horizontal position or a downwardly inclined 80 position.

At its inner end, the handle 50 is formed on the under side thereof with a depending hollow lug 52 having a flat inner face 53 adapted to ride upon the inclined arcuate surface 54, formed on the hollow boss 45. 85 By referring to Figure 4, it will be seen that said hollow boss 45 is provided with a recess or notch 55 of a size and shape to accommodate said hollow lug 52 on the handle when the handle assumes the dotted line position 90 shown in Figure 3. In this position of the handle, corresponding to the dotted lines of Figures 2 and 3, it is obvious that the valve rod 41 cannot be rotated and the openings 17 in the valve plug are made so that the 95 same will be out of register with the openings 16 of the valve casing when the operating handle is in said dotted line or inoperative position.

Due to the fact that tank cars are subject 100 to constant jarring and vibration, it is extremely desirable that the operating handle be prevented from becoming accidentally moved during transit of the car in order to avoid any possibility of the discharge 105 valve accidentally leaking. It is furthermore desirable that the means for retaining the valve operating handle in such closed position operate automatically or in an 110 automatic manner and to this end, I provide a locking plate or latch 56 which is pivoted as indicated at 57 within the upstanding bridge piece 58 made integral with the casting 48. Said latch or locking plate 56 is adapted to swing downwardly, under the 115 influence of gravity, through a slot 59, in the top wall of the casting 58, so as to engage the upper side of the operating handle 50 and positively lock the same in its depressed position, as indicated by the dotted 120 line position of said latch in Figure 2. When it is desired to release the handle 50 in order to open the valve, the latch 56 will be lifted upwardly by oppositely extended finger holds 60 provided in the top 125 edge of the plate.

The notch 55 in conjunction with the handle 50 will obviously determine the closed position of the discharge valve and upon moving the valve to open or discharg- 130

ing position, the handle 50 will swing to the full line position shown in Figure 3 and corresponding limiting stops or lugs may be employed on the valve plug 18, and valve 5 casing 14, one of said lugs being indicated at 61 in Figure 5.

I have herein shown and described what I now consider the preferred manner of carrying out the invention, but the same is 10 merely illustrative and I contemplate all changes and modifications that come within the scope of the claims appended hereto.

I claim:

1. In combination: a tank having a dome; 15 of an outlet valve at the bottom of the tank including a rotatable valve plug; an operating rod extending from said valve plug into the dome and rotatably mounted; an operating handle disposed within the 20 dome and mounted on said rod to swing vertically with respect thereto and to drop under the influence of gravity; a fixed member having an arcuate cam surface approximately concentric with the axis of rotation 25 of said rod, said member having also a shouldered notch therein and the handle having a portion thereof adapted to enter said notch when the handle drops under the influence of gravity, said portion of the 30 handle riding upon said arcuate cam surface during the opening and closing movements of the valve plug; and means for holding said handle in its lowermost position with said portion of the handle in said 35 notch to thereby prevent rotation of the rod accidentally.

2. In a tank outlet valve mechanism of the character described, the combination with a vertically extending rod adapted to 40 actuate the valve proper upon rotation thereof; of a member rigid with said rod and extending laterally therefrom; an operating handle pivotally attached to said member and adapted to drop from a horizontal 45 operating position to a downwardly inclined inoperative position, under the influence of gravity; and a cam-lock movably mounted on said member and arranged to

engage and cooperate with said handle to hold the latter in lowered inoperative position. 50

3. In a tank outlet valve mechanism of the character described, the combination with a vertically extending rotatably mounted valve-operating rod; of a member rigidly 55 secured to said rod and extending laterally therefrom; an operating handle pivotally attached to said member and adapted to swing vertically; a recessed and shouldered plate disposed beneath said member and 60 maintained in fixed position, said plate having a cam-like surface with which the handle is adapted to cooperate when the rod is rotated; and a locking element movably mounted on said member and arranged to 65 engage said handle to hold the latter against upward movement when the handle is engaged with said recessed portion of the plate. 70

4. In a tank outlet valve mechanism of the character described, the combination with a vertically extending rotatable valve-operating rod; of a relatively fixed plate adjacent said rod and having a shouldered notch radially arranged with respect to the 75 rod, said plate having also a concentrically arranged cam-like surface; a member fixed to said rod adjacent said plate extending radially from the rod; an operating handle pivotally attached to said member and 80 adapted to swing vertically and to fall under the influence of gravity, said handle having a depending lug near its pivotal support adapted to fall into said notch and also to ride upon said cam-like surface; and 85 a gravity-controlled pivoted latch mounted on said member arranged to engage the upper side of the handle and lock the same when positioned in said notch.

In witness that I claim the foregoing I 90 have hereunto subscribed my name this 12th day of August, 1920.

EDWARD POSSON.
